UNITED STATES PATENT OFFICE.

FRED STEFFENS, OF ST. JOSEPH, MISSOURI.

SWING.

1,161,264.

Specification of Letters Patent. Patented Nov. 23, 1915.

Application filed January 18, 1915. Serial No. 2,852.

To all whom it may concern:

Be it known that I, FRED STEFFENS, a citizen of the United States, residing at St. Joseph, in the county of Buchanan and State of Missouri, have invented certain new and useful Improvements in Swings, of which the following is a specification.

This invention relates to circle swings and my primary object is to produce a swing having a plurality of seats whereby the occupants are simultaneously carried over a circular course and back-and-forth from points parallel to radial planes of such circular course.

Another object is to produce a swing of the character outlined, provided with mechanism whereby an occupant can drive or quickly arrest the movement of the swing.

Another object is to produce a swing provided with a series of seats disposed circularly and with means for preventing unequal distribution of weight upon the seats from causing the same to travel circularly in appreciably different horizontal planes, regardless of the length of their back-and-forth swinging movements.

Another object is to provide a swing composed of parts which can be easily and quickly assembled in operative relation, and a swing which embodies the desirable features of simplicity, strength, durability, compactness of construction and attractiveness of appearance.

With these and other objects in view, as hereinafter appear, the invention consists in certain novel and peculiar features of construction and organization as hereinafter described and claimed: and in order that it may be fully understood reference is to be had to the accompanying drawings, in which:—

Figure 1, is a side elevation of a swing embodying my invention, with one of the seats and its connections omitted and the other parts broken away to more clearly disclose the construction. Fig. 2, is a top plan view of the swing with the flag and canopy omitted. Fig. 3, is an enlarged vertical section partly broken away taken in the radial plane of one of the power transmitting shafts. Fig. 4, is a horizontal section taken on the line IV—IV of Fig. 3.

In the said drawings, 1 is a base in which is erected in any suitable manner, the central tubular support or column 2, and secured upon said column is a centrally per-

forated cap 3, provided with a plurality of outwardly-projecting radial arms 4, to which are secured radial bars or braces 5 supporting and connecting at their outer ends a circular track 6, preferably of angle iron, the parts 3 to 6 inclusive, constituting a skeleton circular frame.

Secured rigidly to the tubular support or column 2, by clamping collars 7, is a series of substantially U-shaped braces 8. These braces are arranged in the vertical planes of radial bars 5, and for purposes of ornamentation terminate at their ends in scrolls 9. Near their upper ends the braces are bolted rigidly to the bars 5 near the outer ends of the same, through the interposed blocks 10, if desired. At their lower ends the braces 8 are engaged by bolts 11, which extend through the outer ends of radial braces or stays 12, secured at their inner ends at 13, to the base 1. The bolts 11 also extend through a circular ring or band 14, underlying the outer ends of the braces or stays 12, and disposed concentrically with respect to the column, and said ring or band rests upon supports or feet 15, the bolts 11 securing the braces, stays, ring or band and feet firmly together.

Arranged upon the bars or braces 5, and concentrically with respect to the column 2, is a circular casting 16, secured firmly in position by bolts 17, and said casting is provided at its upper side with a circular channel 18, whereby it forms the lower member of a ball race, and with a circular series of radial teeth to constitute a circular rack-bar 19. The parts thus far described constitute what may be conveniently termed the lower or stationary member of the swing.

The upper or rotary member of the swing is constructed as follows: 20 is a cap corresponding to cap 3 but inverted with respect thereto, and provided with outwardly projecting radial arms 21 like arms 4, and secured to the inner ends of said arms are bars or braces 22 corresponding to bars 5, and said bars or braces 22 are connected at their outer ends by a ring or band 23, corresponding to ring or band 6 but inverted with respect thereto. It will thus be seen that parts 20 and 23 inclusive are of interchangeable construction with respect to parts 3 to 6 inclusive.

24 are bolts for securing in fixed relation to and below the bars 22, a circular ball-bearing member 25, which member is of the

same diameter as and disposed above member 16 and rest upon balls 26 in channel 18, the member 25 being provided with a similar ball race or channel 27.

5 As it is necessary to make provision for other parts hereinafter mentioned between the two sets of bars 5 and 22, it is desirable to space the member 25 some distance below the plane of the bars 22, and to accomplish this purpose, spacing tubes or sleeves 28 are fitted upon the bolts 24 and bear at their upper and lower ends respectively, against bars 22 and member 25, as shown clearly in Fig. 3.

15 To brace the radial bars 22 near their outer ends for the purpose of maintaining the ring or band 23 in rigid relation to the cap 20, a tubular post 29 is secured at its lower end in cap 20, and secured to said 20 post about midway its height by a collar 30, is a series of inclined curved braces 31, occupying the vertical planes of bars 22, and secured at their lower or outer ends to the outer ends of said bars, as shown most 25 clearly in Fig. 3.

As a means of guarding against any possibility of dislocation of the upper ball-bearing member 25, a rod 32 is arranged centrally within post 29, and secured rigidly at its upper end at 33, to said post. The rod extends downward through the caps 20 and 3 and into column 2, its lower end engaging a ball-bearing 34, secured within said column, so as to turn therein 35 with a minimum friction. The rod 32 not only guards against the dislocation of the member 25 but also against tilting action of the superstructure, which is that part above the lower or stationary part of 40 the swing.

Arranged in a horizontal plane above the ring or band 23, is a pair of concentric rings 35 and 36, both of greater diameter than the ring or band 23, as shown clearly by 45 Fig. 2, and to support these rings in concentric relation to the axis of column 29, I employ inclined supporting rods 37 and 38, respectively secured at their lower ends to said rings and hooked at their upper ends 50 upon pins 40 of a cap or collar 39, secured upon the upper end of post 29. The cap or collar provides a convenient support for a flag staff 41, which, of course, is for decorative purposes only.

55 At equal distances apart U-shaped hanger rods 42 connect the rings 35 and 36. These hanger rods are arranged in pairs parallel with and disposed at opposite sides of and equal distances from radial planes intersecting the axis of the column. The pairs of rods extend convergently inward with respect to adjacent pairs and thus rigidly connect the rings 35 and 36 together.

Pivots pend from each set of 60 hanger rods are hanger bars 43, pivotally

connected at their lower ends by foot platforms 44, within convenient reach of a seat 45, supported through the engagement of the serrated edges 46 of the seat, with a cross rod 47 connecting the rearmost pair of 70 each set of bars 43, the seat being also connected pivotally to said bars by inclined braces 48, to accommodate adjustment of the seat on the rods 47, (see Fig. 1). The adjustment of the seat is for the accommodation of persons of different height or for 75 their comfort, the upper member can be caused to rotate to effect travel of the swings around the lower member, and said swings can be caused to swing or oscillate 80 through the occupant of a seat alternately exerting foot pressure on the companion platform 44, and relaxing such pressure, the operation being made easy when all of the 85 occupants of the seats coöperate. More specific reference to the operation referred to will be found hereinafter.

For the purpose of imparting rotary movement to the upper or rotary member and swinging movement to the individual seats, 90 of which four are shown, but of which there may be any number compatible with safety from conflict, or for regulating or arresting the operation of the upper member and individual seats or swings, foot platforms 95 49 are pivoted at their front ends upon cross-rods 50 connecting the foremost pairs of the sets of bars 43. The inner rear corner of each platform 49 is pivotally connected by a pitman link 51, to a lever 52, pivoted at 100 its front end with respect to the direction of rotation, to a V-shaped frame 53 secured to the adjacent bar 43, in any suitable manner. To stiffen and brace the platform 49 at its rear outer corner, a curved brace 54 extends upwardly and inwardly from the said outer corner of the platform to the said link 51, as shown clearly in Fig. 1. The rear end of each lever 52 is pivotally connected to the crank-arm 55 of a radially 110 extending shaft 56, journaled in a pair of hangers 57 and 58, depending respectively from the upper or rotary member of which bars 22 and ring or band 23 constitute parts, the hangers 58 being disposed in the vertical plane of ring or band 6, and provided with rollers 59, which are adapted under the slightest tilting or springing action of the said rotary member to engage the underlying circular track or band 6. The inner end of each shaft 56 is equipped with a bevel gear 60, engaging the circular rack 19, for the purpose of transmitting power from the oscillatory foot platform 49 to the rotary member of the swing. 115

To shade the occupants of the swing from the sun at midday, the swing may be provided with a canopy or cover 61 which can be conveniently arranged upon the inclined brace rods 38, as shown by Fig. 1, which 120

canopy, of course, also gives the swing a finished appearance.

Assuming that one or more of the seats are occupied, it will be seen that the application of pressure through the occupant's feet upon the adjacent platform 49, will rock the same downward and hence through link 51 rock the connected lever 52 and impart rotation to the connected crank shaft 56, which shaft through the intermeshing of its gear 60 with the circular stationary rack-bar 19, will effect rotation of the upper member or superstructure of the swing. As it is obvious that the lever 52 must have endwise movement in order to accommodate the rotation of the crank of said shaft, the associated swing bars 43 are caused to swing, because the lever is fulcrumed at a point fixed with relation to said swing bars, that is to say, on the V-shaped frame which is carried by a pair of said swing bars.

As the foot pressure upon the platform 49 is relaxed the momentum acquired by the superstructure effects the reëlevation of the foot platform through the lifting pressure applied by the crank of the shaft on lever 52, the next application of foot power on the platform 49 effecting a repetition of the operations described though with less exertion on the part of the operator because the speed of rotation of the superstructure will have become more rapid. It is obvious that the application of foot power by the occupants of other seats, will aid in the propulsion of the swing and render its operation easy. It will also be apparent that the foot platforms 49 enable the occupants to check the speed gradually or quickly if an emergency arises by applying pressure on the foot platforms as they rise after each depression.

It is to be understood that the machine can be efficiently operated regardless of the presence of the pivoted foot platforms 49 and links 51, as the application of pressure on the foot platforms 44 by the occupants of the seats will effect swinging movement of the swinging hanger bars 43, and said bars, through their frames 53 will move the levers 52 endwise. As said levers are pivotally connected at their free ends to the crank shafts, endwise movement back and forth will impart rotary movement to the crank shafts and hence cause the upper member to rotate upon the lower or stationary member.

It will be apparent that if there is a much greater preponderance of weight on one of the seats than upon a seat at the opposite side of the column, the roller 59 adjacent the more heavily loaded seat will come in contact with and roll upon the circular track 6 and thus maintain the more heavily loaded seat substantially in the same horizontal plane as the opposite or lightly loaded seat,

and incidentally maintain substantially the same pressure upon the balls of the ball bearings. The central rod of course coöperates with the ball bearing between the top of the stationary member and the superstructure in maintaining said parts in concentric relation with respect to the axis of rotation.

From the above description it will be apparent that I have produced a circle swing possessing the features of advantage enumerated as desirable, and I wish it to be understood that while I have shown and described what now appears to be the preferred embodiment of the invention, I reserve the right to make all changes falling within the spirit and scope of the appended claims.

I claim:

1. A swing comprising a lower or stationary member, an upper or rotary member mounted on the stationary member, series of hanger bars pivotally suspended from the upper member, foot platforms pivotally carried by the hanger bars of different series, a seat carried by each series of hanger bars and means whereby swinging movement of a series of the hanger bars shall impart rotary movement to said upper or rotary member.

2. A swing comprising a lower or stationary member, an upper or rotary member mounted on the stationary member, series of hanger bars pivotally suspended from the upper member, foot platforms pivotally carried by the hanger bars of different series, a seat carried by each series of hanger bars, a lever carried by each series of hanger bars and means whereby the operation of said lever shall impart rotation to said upper or rotary member.

3. A swing, comprising a stationary member having a circular track, a rotary member mounted on the stationary member and spaced above the said track, a plurality of hanger bars, swingingly suspended from the rotary member, a foot platform pivotally carried by the hanger bars, a seat carried by the hanger bars, a lever carried by the hanger bars and having movement in a vertical plane, a crank shaft for operation by said lever and means for transmitting power from the crank shaft to the upper member to rotate same.

4. A swing comprising a stationary member and a rotary member, one or more seats swung from the rotary member, a crank shaft geared to turn the rotary member, a lever movable bodily with each seat, and also pivotally independently thereof and connected to the shaft to rotate the same, and foot-operated means for pivotally operating the lever.

5. A swing comprising a stationary member and a rotary member, swing bars sus-

pended from the rotary member, a foot platform carried by said bars, a seat carried by the bars, a foot platform pivoted to certain of said bars, a lever carried by certain of said bars, a link pivotally connecting the pivoted foot platform with said lever, and a shaft for the seat, geared to and carried by the rotary member and provided at its outer end with a crank pivotally engaged by said lever.

6. In a swing, a lower or stationary member embodying a vertical column and a horizontal circular track arranged concentrically of the column, an upper rotary member having an anti-friction support upon the lower member, a central vertical rod connected to the column and the central portion of the upper member and fixed with relation to one of them and having an antifriction bearing relation with the other, seats swingingly suspended from the upper member, and means controlling the rotation of the upper member and the swinging of each seat.

7. In a swing, a lower stationary member embodying a vertical column and a horizontal circular track arranged concentrically of the column, an upper rotary member having an antifriction support upon the lower member, a central vertical rod connected to the column and the central portion of the upper member and fixed with relation to one of them and having an antifriction bearing relation with the other, seats swingingly suspended from the upper member, means controlling the rotation of the upper member and the swinging of each seat, and antifriction means for limiting tilting or springing movement of either of the members without interfering with the freedom of rotation of the upper member.

8. In a swing, a lower stationary member embodying a vertical column and a horizontal circular track arranged concentrically of the column, an upper rotary member having an antifriction support upon the lower member, a central vertical rod connected to the column and the central portion of the upper member and fixed with relation to one of them and having an antifriction bearing relation with the other, a horizontal skeleton frame supported by and in rigid relation to the upper rotary member, hanger bars carried by said frame, two pairs of swing bars suspended from the hanger bars and adapted to swing at right angles to radial planes

intersecting the axis of the rotary member, a platform pivotally connected to the lower ends of each pair of hanger bars, a seat carried by a pair of each set of hanger bars connected by the platform, a pivoted foot platform adjacent each seat and carried by certain of said hanger bars, and means for transmitting power from the pivoted platform to the rotary member to simultaneously rotate the same and swing the swing bars.

9. In a swing comprising a lower or stationary member and an upper or rotary member mounted rotatably upon the lower member, a pair of horizontal rings arranged concentrically of the axis of the rotary member, inclined braces extending inwardly and upwardly from said rings and fastened to the upper end of the rotary member, sets of hanger bars connecting the inner and outer rings and extending parallel with and at opposite sides of a radial plane intersecting the axis of rotation of the rotary member, seats swung from said hanger bars, connections between certain seats and the upper or rotary member whereby the operation of said connections shall simultaneously effect rotation of the rotary member and swinging movement of the seats, and manually operable means under the control of the occupants of the seats for operating said connections or for checking their operation.

10. In a swing, a lower or stationary member provided with a circular track at its upper end, an upper rotary member having an anti-friction support on the lower member and provided with a ring above said track, an axial rod connecting the stationary and rotatable member to prevent undue tilting or lateral movement of the latter, seats swung from the upper member and disposed around the lower member, manually controlled means for effecting simultaneous rotation of the upper member and swinging movement of said seats, and rollers suspended from the ring of said upper member and adapted under slight tilting or downward springing movement thereof to engage and travel upon the circular track of the lower or stationary member.

In testimony whereof, I affix my signature, in the presence of two witnesses.

FRED STEFFENS.
